(57) **CLAIM**

The ornamental design for a keyboard cover, as shown and described.

DESCRIPTION

FIG. 1 is a front, top perspective view of a keyboard cover, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1;

FIG. 10 is an enlarged view of detail "10" identified in FIG. 2;

FIG. 11 is another perspective view of the keyboard cover shown in a position of use;

FIG. 12 is another perspective view thereof, shown in an alternative position; and,

FIG. 13 is another perspective view thereof, shown in an alternative position.

The dash-dot-dash broken lines in FIGS. 1, 2, 9 and 10 are for the purpose of illustrating the enlarged view indicators and are for the purpose of illustrating portions of the keyboard cover and environment that forms no part of the claimed design. The evenly spaced broken lines are shown for the purpose of illustrating portions of the keyboard cover and environment that form no part of the claimed design.
